H. W. SMITH

CLOSURE FOR FUEL TANKS

Filed Sept. 27, 1923

Fig. 2.

Inventor:
Harry Worcester Smith
by Owen W. Kennedy
Attorney

Fig. 3.

UNITED STATES PATENT OFFICE.

HARRY WORCESTER SMITH, OF NORTH GRAFTON, MASSACHUSETTS.

CLOSURE FOR FUEL TANKS.

Application filed September 27, 1923. Serial No. 665,120.

To all whom it may concern:

Be it known that I, HARRY WORCESTER SMITH, a citizen of the United States, residing at North Grafton, in the county of Worcester and Commonwealth of Massachusetts, have invented a new and useful Improvement in a Closure for Fuel Tanks, of which the following, together with the accompanying drawings, is a specification.

10 My invention relates to a closure for fuel tanks, such as are carried by motor vehicles for the retention of gasoline or other liquid fuel.

The object of my invention is to provide an improved closure which, in one position, will effectively seal the opening of the tank, and which, in another position, will uncover the opening so that the tank may be filled, the closure being permanently attached to the tank.

The most usual and well known form of closure for fuel tanks is the screw cap which, while entirely effective in sealing the tank, is open to the serious objection that it must be entirely removed therefrom when it is desired to fill the tank. Consequently, careless operators at filling stations often neglect to screw the cap on again after filling the tank, with the result that the cap is lost and a great annoyance caused to the driver of the vehicle. Various other forms of closures have been employed embodying a clamping or locking device, but even these closures are open to the objection that they require some manipulation in order to effectively seal the tank opening.

According to the present invention I provide a tank closure which is characterized by the fact that it is permanently attached to the tank and so cannot be lost, and that it may be readily moved from an open to a closed position by the application of a slight force that may be conveniently applied by the metallic nozzle of the hose, with which most filling stations are equipped. The above and other advantageous features of my invention will hereinafter more fully appear, reference being had to the accompanying drawings in which

50 Fig. 1 is a view in front elevation, showing a portion of a fuel tank with my improved closure attached thereto.

Fig. 2 is a transverse sectional view along the line 2—2 of Fig. 1.

55 Fig. 3 is a plan view of the parts shown in Fig. 1.

Like reference characters refer to like parts in the different figures.

Referring to the drawings, a portion of a fuel tank is indicated at 1 and is provided with an upwardly extending cylindrical flange 2, the upper end of which is open for the entrance of fuel into the tank 1. The flange 2 may be located at any desired portion of the tank where its fuel opening will be most convenient, and it is only necessary that the flange 2 be of such height that my closure can be readily mounted thereon, as will now be described.

The closure consists of a generally hollow, cylindrical shell 3 which is provided with arms 4, by means of which it is pivotally mounted on pins 5 projecting from the flange 2. The upper end of the shell 3 is closed, while its lower end is somewhat constricted, as indicated at 6, to retain a ball 7 partly within the shell 3. A spiral spring 8 is located within the shell 3 and normally tends to maintain a portion of the ball 7 beyond the lower end of the shell 3.

In the full line position of the closure, the projecting portion of the ball 7 is seated in the open end of the flange 2, and is held firmly in position by the spring 8 to effectively seal the opening to the tank. The pressure of the spring 8 is sufficient to maintain the ball 7 in this position, so that the vibrations attendant the running of the vehicle over rough roads, will not unseat the ball 7, and permit fuel to escape from the tank.

The top of the shell 3 is provided with a lug 9, the sides of which are concave and have about the same radius of curvature as the metal nozzles commonly provided on the hose of filling stations. When it is desired to move the closure so as to uncover the end of the flange 2, it is only necessary for the operator of the filling station to strike the lug 9 a sharp blow with the nozzle of the hose, thereby exerting a strong turning moment on the shell 3 about the axis of the pivot pins 5. The resulting force exerted on the ball 7 by the rim of the flange 2 overcomes the pressure of the spring 8 and causes the ball 7 to be forced upwardly into the shell 3 enough to clear the flange 2, thus exposing the open end of the same.

When the closure is thus moved from its vertical position, the ball 7 is adapted to be received in a concave seat 10 provided in a wing 11 projecting from the flange 2. The

closure then occupies the position shown in dotted lines in Fig. 1, and it is apparent that the spring 8 will then act to retain the ball 7 in the seat 10 in the same manner as it originally maintained the ball in the fuel opening. In this position of the closure, the fuel opening is entirely uncovered, so that the tank may be readily filled, after which, all that is necessary to close the fuel opening, is for the person who has filled the tank to return the closure to a vertical position by a single blow.

In order to prevent the seat 10 from becoming covered with dirt, which might be carried into the tank, a shield 12 is provided on the shell 3, which shield covers the seat 10 when the closure is in a vertical position.

From the foregoing it is apparent that by my invention I have provided an improved closure for fuel tanks, which is adapted to be yieldingly maintained in either an open or closed position, so that the closure may be moved from one position to another by the striking of a light blow. The force necessary to move the closure need not be very great, by reason of the fact that it is applied through a relatively long lever arm, the force exerted by the spring 8 being just sufficient to hold the ball seated in either position against ordinary vibrations. It is obvious that the closure cannot be lost or even readily removed from the tank, and that the effort required to move the closure to seal the tank after being filled, is so slight as to insure that the tank will not be accidentally left open. When my closure is applied to a

tank used with a vacuum fuel feed system, a suitable vent may be provided in the flange 2, as indicated in dotted lines at 13.

I claim:

1. In a closure mechanism for tanks, a member provided with an orifice, a hollow member pivotally attached to said first member, a spherical member in said hollow member, means retaining said spherical member at least partially in said hollow member, resilient means tending to press said spherical member out of said hollow member, a flange on said first named member to receive said spherical member when the closure mechanism is in the open position, a concave seat on said flange, and a second flange on the hollow member adapted to cover said first named flange when the closure mechanism is in the closed position.

2. In a closure mechanism for tanks, a member provided with an orifice, a hollow member pivotally attached to said first member, a spherical member in said hollow member, means retaining said spherical member at least partially in said hollow member, resilient means tending to press said spherical member out of said hollow member, a flange on said first named member to receive said spherical member when the closure is in open position, and a cooperating flange on the hollow member adapted to cover said first named flange when the closure member is in the closed position and to serve as a stop to limit the opening movement of the said hollow member with the spherical member.

HARRY WORCESTER SMITH.
